UNITED STATES PATENT OFFICE.

ALFRED COHN, OF MILWAUKEE, WISCONSIN.

KNITTED CAP.

Application filed October 14, 1921. Serial No. 507,668.

To all whom it may concern:

Be it known that I, ALFRED COHN, a citizen of the United States, residing at Milwaukee, county of Milwaukee, and State of Wisconsin, have invented new and useful Improvements in Knitted Caps, of which the following is a specification.

My invention relates to improvements in knitted caps.

- 10 The object of this invention is to provide improved means for utilizing the cap band as a covering for the ears, chin, and the exposed portions of the neck of the user when protection is needed for these parts of the head, the band being also adapted to be adjusted upwardly at the front of the cap to form a continuation of a permanently attached rear portion secured to the crown in a raised position.

20 In the drawing:

Figure 1 is a side elevation of my improved cap with the band in its raised or normal position.

Figure 2 shows the cap in position on the head of a wearer as it appears when adjusted to ear and neck covering position.

Like parts are identified by the same reference characters in both views.

The body A of the cap may be knitted in an ordinary manner, and the portions B and C constituting the band may be either formed integrally or separately as may be desired. The portion B of the band is connected with the crown along the lower margin as indicated at D, and it is also connected with the crown by stitching along the oblique lines E from the lower margin to the upper margin on each side of the crown, the line of stitching extending upwardly and rearwardly as shown.

The other portion C of the band, which preferably constitutes its major portion, is unconnected with the crown except by the lines of stitching E. This portion C may be knitted integrally with the portion B, or if desired it may be separately formed and connected therewith by the stitching along the lines E. The portions B and C, however, are preferably formed integrally for the reason that a cap so made is neater in appearance than one in which the band portions are separately formed and stitched together.

For a similar reason the band is preferably formed or knitted as an independent

strip of material to be subsequently connected with the crown, the ends of the strip being brought together at the rear of the crown and connected by a line of stitching F, which however need not connect the band with the crown, inasmuch as the portion B is held to the crown by the stitches at D and E. If the band is originally formed integrally with the crown, it is necessary to disconnect the portion C along the lower margin and then finish the edges by over-stitching, whereas when the band is separately produced, these margins have a selvaged edge.

In use, the cap may be worn in mild weather with the band in the position in which it is shown in Figure 1. But in inclement weather the portion C may be adjusted over the ears, under the chin, and about the neck by swinging it downwardly with a turning or inverting movement about the lines E as axes to reverse the relative positions of the band margins G and H, whereby the margin G becomes the lower or rear margin and the margin H, the upper or forward margin, extending along the chin of the wearer as shown in Figure 2.

It will be understood that the band portion C is turned inside out, i. e., the face that is concealed when in the raised position is exposed when the portion C is adjusted under the chin of the wearer.

When the band is adjusted to the Figure 1 position, the cap has the appearance of an ordinary knitted cap with a plain band of uniform width encircling the lower portion of the crown, but with diagonal crease lines (the lines E) at the sides and a little to the rear of the center. But when the portion C is swung downwardly and adjusted to the position in which it is illustrated in Figure 2, the cap becomes, in effect, a cap of the type known as a helmet cap, although wholly different in construction from that of a helmet cap and better adapted to fit snugly upon the ears along and between its respective margins G and H. The inversion of the band when being swung downwardly, and its connection with the crown along the oblique lines E at the sides of the crown, have the effect of causing the band to retain its shape and to draw with uniform tension against the portions of the head which it covers.

The invention is particularly applicable to knitted caps in which a serious problem is

usually presented where any of the parts are subjected to greater tension than the other parts, of providing means for avoiding distortion due to the stretching of the threads, 5 and to the fact that they may, to a greater or less extent, be drawn longitudinally out of those portions of the fabric which are under less tension. Therefore, great importance is attached to the fact that the swinging portion of the band in my improved cap is under substantially uniform tension throughout its area when swung downwardly, and the threads which connect it with the other portion B of the band are secured to the body by stitches along the lines 10 E, thus preventing the tension from being extended into the portion B.

I claim:

1. A knitted cap comprising the combination with a crown having an encircling band secured to the crown along oblique lines extending upwardly and rearwardly from the lower side margins, the front portion of said band being free from the crown and 20 adapted to be swung downwardly with a turning movement upon an axis corresponding with said oblique lines of connection, 25

whereby such portion may be engaged underneath the chin of the wearer in a neck and ear covering position.

30

2. A cap having the crown encircled by a band free from the crown at the front, the rear portion of said band being secured to the crown along oblique lines converging upwardly and rearwardly from the sides and 35 adapted to hold the rear portion of the band in a permanently raised position while allowing the front portion to be swung downwardly with a folding movement upon the lines of connection as an axis, to an ear and 40 neck covering position, with the downwardly swung portion engaged under the chin of the wearer.

3. A cap comprising a crown and a band encircling said crown, and free from said crown at the front, said band being secured to said crown along diagonal lines extending upwardly and rearwardly from the side portions and secured to said crown at the rear portion, whereby the free front portion of 45 said band may be swung downwardly to a position beneath the chin of a wearer without disturbing the rear portion of the band.

ALFRED COHN.
